[57] CLAIM

The ornamental design for a picture holding mobile, as shown and described.

DESCRIPTION

FIG. 1 is a front, top perspective view of a picture holding mobile showing my new design;

FIG. 2 is a top plan view thereof;

FIG. 3 is a bottom plan view thereof;

FIG. 4 is a side elevational view thereof;

FIG. 5 is a front, top perspective view of a picture holding mobile showing a further embodiment of my new design;

FIG. 6 is a front, top perspective view of a picture holding mobile showing yet another embodiment of my new design;

FIG. 7 is an isolated perspective view showing a transparent picture holder of my new design;

FIG. 8 is a front elevational view of the picture holder of FIG. 7; and,

FIG. 9 is a side elevational view of the picture holder of FIG. 7.
